CLAIM

The ornamental design for a toaster cover, as shown and described.

DESCRIPTION

FIG. 1 is a perspective view of the toaster cover showing my new design;

FIG. 2 a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a perspective view of the toaster cover shown in an environment of use.

The broken lines showing a toaster in FIG. 8 illustrate environment and form no part of the claimed design.
